CLAIM

The ornamental design for a bottle, as shown and described herein.

DESCRIPTION

FIG. 1 illustrates a front perspective view of a bottle, showing our new design;

FIG. 2 illustrates a front elevation view thereof;

FIG. 3 illustrates a rear elevation view thereof;

FIG. 4 illustrates a right side elevation view thereof;

FIG. 5 illustrates a left side elevation view thereof;

FIG. 6 illustrates a top view thereof;

FIG. 7 illustrates a bottom view thereof; and,

FIG. 8 illustrates a cross-sectional view thereof, taken along line VIII—VIII in FIG. 7.

The broken line showings of the bottle neck and bottom contours are for illustrative purposes only and form no part of the claimed design.
